CLAIM

The ornamental design for pulse oximeter with integrated sensor, as shown and described.

DESCRIPTION

FIG. 1 is a perspective view of a pulse oximeter with integrated sensor showing our new design, with the integrated sensor in the closed position;

FIG. 2 is a top plan view thereof;

FIG. 3 is a bottom plan view thereof;

FIG. 4 is a left side elevational view thereof;

FIG. 5 is a right side elevational view thereof;

FIG. 6 is front elevational view thereof with the integrated sensor in the closed position;

FIG. 7 is a rear elevational view thereof; and,

FIG. 8 is a perspective view thereof with the integrated sensor in the open position.

The broken lines in the drawing views are included for the purpose of illustrating portions of the pulse oximeter with integrated sensor that form no part of the claimed design.
